(57) **CLAIM**

The ornamental design for a beverage bottle, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front elevation view of a beverage bottle showing the claimed design;

FIG. 2 is a first side elevation view thereof;

FIG. 3 is a second side elevation view thereof, opposite the first side elevation view;

FIG. 4 is a rear elevation view thereof;

FIG. 5 is an elevation view showing the rear and second side thereof;

FIG. 6 is an elevation showing the front and second side thereof;

FIG. 7 is a top plan view thereof;

FIG. 8 is a top perspective view thereof;

FIG. 9 is a bottom plan view thereof;

FIG. 10 is a bottom perspective view thereof, showing a detail of the front and first side; and,

FIG. 11 is a bottom perspective view thereof, showing a detail of the front and second side.
